UNITED STATES PATENT OFFICE.

ROLLIN WHITE, OF LOWELL, MASSACHUSETTS.

IMPROVEMENT IN CARTRIDGE-EJECTORS FOR REVOLVERS.

Specification forming part of Letters Patent No. 179,084, dated June 20, 1876; application filed May 23, 1876.

To all whom it may concern:

Be it known that I, ROLLIN WHITE, of Lowell, in the county of Middlesex and State of Massachusetts, have invented a new and useful Improvement in Cartridge-Ejectors for Revolvers; and I do hereby declare that the following is a full and exact description of the same, reference being had to the accompanying drawings, and to the letters of reference marked thereon.

The object I have in view is an improvement in cartridge-ejectors for breech-loading cylinder fire-arms, by which the same may be more convenient and effective in operation; and the novelty therein consists, principally, in swiveling or pivoting the ejector in front of the cylinder in such a way that the operation of the ejector shall revolve the cylinder, so as to bring one chamber at a time in line with the discharge-barrel, and also in the various operative combinations of the principal parts of the mechanism which effect the above-named result.

In order that those skilled in the art may know how to make and use my improvement I now describe the same in connection with the drawings, in which—

Figure 1 is a view of a pistol, with the ejector in position in front of the cylinder, and showing in dotted lines the ejector in position within a chamber of the cylinder; Fig. 2, a separate view of the ejector; Fig. 3, a modification of Fig. 1, showing the ejector connected with, and operated by, either the hammer or the trigger of the pistol; Fig. 4, a modification of the ejector shown in Figs. 1 and 2, and Fig. 5 a cross-section on the line $x x y$, Fig. 4.

Like letters denote corresponding parts in each figure.

In the drawings, A represents the cylinder, with chambers a passing through the same, and B the discharge-barrel of the pistol, and C a rod rigidly secured under the barrel, upon which the ejector D is swiveled or pivoted. This ejector is composed of a hollow shank, b , through which the rod C passes, a shoulder, c , at the inner end of said shank, an arm, d , secured to the end of the shoulder, and a spiral spring, e , which encircles the rod

C, and is secured at one end to such rod and at the other end to the shank b . Upon one side of the barrel B is secured an incline, E, tapering to the front. Upon the outside of the shoulder c there may be a suitable thumb-piece, f , and, if need be, other projections f' f'' upon the shank, to give a better grasp to the hand of the operator.

It will be seen, then, that, supposing one or more chambers of the pistol to be discharged, and the operator desires to remove the cartridge, he causes the end of the ejector-arm to enter the chamber of the cylinder most convenient to it, and, forcing the ejector into such chamber, the shoulder c runs up the incline E, by means of which the ejector is rotated sufficiently to rotate the cylinder the desired distance. The ejector-arm, passing through one of the chambers of the cylinder, backs the cartridge-shell out of the same, and when released by the hand by means of the spring e , the incline returns to its normal position in front of the cylinder. It will be seen, however, that instead of having this ejector operated directly by the hand upon its shank, it can be operated readily by the hammer, or by the trigger, as shown in Fig. 3, by means of connections pivoted to the shank, and to the hammer or trigger, respectively.

In the modification shown in Fig. 4, instead of having the shank b secured to the ejector-arm d , and having such shank slide upon the rod C, the shank is pivoted upon the inner end of such rod, which in this case needs only to be long enough for that purpose, and the ejector-arm d passes through the shank, and instead of the shoulder c upon the shank to ride upon the incline E, this shoulder c is upon the ejector-arm, the operation in each instance being identically the same, it being evident that the ejector-arm must not rotate within the shank, to prevent which it may be made angular or grooved, or have any of the ordinary appliances to produce the desired result.

The advantages of my contrivance are obvious upon inspection, as it will enable the manufacturer to dispense with expensive and delicate machinery connected with the rotation of the cylinder, and avoids the liability of such machinery to get out of order, will

enable the ejection of the cartridge-shell to be more certain, and will be equally efficacious to back out a loaded shell, if desired.

My improvement, however, can be readily applied to all breech-loading cylinder firearms where the cylinder is rotated by the movement of the hammer or of the trigger, or in any other known way.

Having thus described my invention, what I claim as new therein is—

1. In combination with a breech-loading cylinder fire-arm, a cartridge-ejector, swiveled or pivoted in front of the same, and adapted to rotate the cylinder while it is ejecting the cartridge, or be rotated by such cylinder, substantially as described.

2. In combination with a cartridge-ejector

having a shoulder, *e*, an incline, *E*, upon the pistol, substantially as and for the purposes set forth.

3. In combination with a cartridge-ejector and the rod *C*, the spring *e*, secured at one end to such rod and at the other end to the ejector, by which the torsional force of the spring is exerted to partially rotate the ejector-stem when it is withdrawn from the chamber for the purpose of returning it to its normal position.

This specification signed and witnessed this 23d day of May, 1876.

ROLLIN WHITE.
